(57) **CLAIM**

The ornamental design for a chick heating plate, as shown and described.

DESCRIPTION

FIG. 1 is a front, right, top perspective view of the chick heating plate in the first usage state;

FIG. 2 is a rear, left, bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view of the reduced scale thereof;

FIG. 8 is a bottom plan view of the reduced scale thereof;

FIG. 9 is an enlarged view of detail 9 in FIG. 1;

FIG. 10 is an enlarged view of detail 10 in FIG. 1;

FIG. 11 is an enlarged view of detail 11 in FIG. 1;

FIG. 12 is an enlarged view of detail 12 in FIG. 2;

FIG. 13 is an enlarged view of detail 13 in FIG. 2;

FIG. 14 is a front, right, top perspective view of the chick heating plate in the second usage state; and,

FIG. 15 is a front, right, top perspective view of the chick heating plate, indicating the usage environment.

The dashed broken lines illustrate portions of the chick heating plate which form no part of the claimed design.

The short-short-long dashed broken lines immediately adjacent to the claimed areas in the views represent the boundaries of the design and form no part of the claimed design.

The dash-dot-dash broken lines are for notating enlarged views and form no part of the claimed design.

The broken lines in FIG. 15 are for environmental purposes only and form no part of the claimed design.
